UNITED STATES PATENT OFFICE.

DUDLEY T. BOSTON, OF GARFIELD COUNTY, OKLAHOMA TERRITORY.

RETURN-ENVELOP.

No. 827,208.

Specification of Letters Patent.

Patented July 31, 1906.

Application filed May 31, 1905. Serial No. 263,111.

To all whom it may concern:

Be it known that I, DUDLEY T. BOSTON, a citizen of the United States, residing in the county of Garfield, Territory of Oklahoma, have invented certain new and useful Improvements in Return-Envelops, of which the following is a specification.

This invention relates to an improved return-envelope; and it consists, essentially, of an envelop of the usual construction except that it is provided with a series of removable address-slips and also with a corresponding series of sealing-slips.

The object of the invention is to provide an envelop which can be sent back and forth a certain number of times and is designed particularly for advertising purposes.

For a full description of the invention and the merits thereof and also to acquire a knowledge of the details of construction of the means for effecting the result reference is to be had to the following description and accompanying drawings, in which—

Figure 1 is a perspective view showing the envelop open. Fig. 2 is a transverse sectional view showing the envelop closed. Fig. 3 is a vertical sectional view. Fig. 4 is a transverse sectional view showing a modification.

Corresponding and like parts are referred to in the following description and indicated in all the views of the drawings by the same reference characters.

The numeral 1 designates the envelop, and 2 the flap thereof. A series of address-slips 3 are attached one upon the other to the face of the envelop by folding their ends backward and securing them by glue or other suitable means to the rear of the envelop, as seen at 4 in the drawings. It will thus be seen that these address-slips 3 do not constitute a part of the envelop proper, but are simply designed to receive the address. Break-lines 5, which may take the form of a line of perforations, as seen in the drawings, are provided at each end of the address-slips 3, so that they can be easily and quickly torn off after being used. A corresponding series of sealing-slips 6 are secured one upon the other at one of their ends to the upper portion of the flap 2, and said slips are constituted by tabs or strips, as shown, projecting

from the said flap 2. In use it is intended to fold the flap 2 and all of the sealing-slips 6 except the top one within the envelop, the top one being used to seal same. A break-line 55 7 is also provided in the sealing-slips to enable them to be easily torn off when desired. The number of times which this envelop can be used depends upon the number of address-slips and sealing-slips with which it is formed. 60 When this envelop is employed to send matter which does not require to be sealed, the flap may be secured by a spring-fastening, as seen at 8.

In practice the address is written upon the 65 outermost address-slip and the envelop sealed, as has been heretofore described, by the outermost sealing-slip after the flap 2 and the remaining sealing-slips have been folded within the envelop. The recipient simply 70 tears off the address-slip and sealing-slip which have been used and repeats the above operation, which may continue until all of the address-slips and sealing-slips have been used. It will be observed that by the employment of my device any envelop can be 75 transformed into a return-envelope.

Having thus described the invention, what is claimed as new is—

1. In combination with an envelop or 80 analogous receptacle having a closing-flap, of a series of sealing-tabs in book form attached at one end to one another and to the said closing-flap near its juncture or line of fold with the body of the envelop, and having the 85 other ends of the tabs loose and projected beyond the edge of the closing-flap and adapted to have the outermost one attached to the envelop to seal and fasten the same, the remaining tabs being protected and covered 90 by the part of the envelop to which the outermost sealing-tab is attached.

2. In combination with an envelop or 95 analogous receptacle having a closing-flap, of a series of address-slips coextensive with the length and breadth of the envelop and having their end portions attached to one another and to the respective end portions of the envelop, and having the intermediate portions of the said slips loose and separated by break-lines from the attached end portions, and a corresponding number of sealing-tabs attached 100

at one end to one another and to the said closing-flap near its juncture or line of fold with the body of the envelop, and having the other ends of the tabs loose and projected beyond the edge of the closing-flap and adapted to have the outermost one attached to the envelop to seal and fasten the same, the remaining tabs being protected and covered by

the part of the envelop to which the outermost sealing-tab is attached.

In testimony whereof I affix my signature in presence of two witnesses.

DUDLEY T. BOSTON. [L. S.]
